Primary Examiner — Daniel Bui(74) *Attorney, Agent, or Firm* — Sheridan Ross P.C.(57) **CLAIM**

The ornamental design for an electrical connector, as shown and described.

DESCRIPTION

FIG. 1 is a front, top and left side perspective view of an electrical connector showing our new design;

FIG. 2 is a front, top and right side perspective view thereof;

FIG. 3 is a front elevation view thereof;

FIG. 4 is a top plan view thereof;

FIG. 5 is a bottom plan view thereof;

FIG. 6 is a left side elevation view thereof; and,

FIG. 7 is a right side elevation view thereof.

The broken line in FIGS. 4 and 5 are included for the purpose of illustrating unclaimed environment only and forms no part of the claimed design.
